UNITED STATES PATENT OFFICE.

CHARLES B. JAYNES, OF BIRMINGHAM, ALABAMA.

ROOFING.

1,418,377.

Specification of Letters Patent. Patented June 6, 1922.

Application filed July 3, 1920. Serial No. 393,776.

To all whom it may concern:

Be it known that I, CHARLES B. JAYNES, a citizen of the United States of America, residing at Birmingham, in the county of 5 Jefferson and State of Alabama, have invented certain new and useful Improvements in Roofing, of which the following is a specification.

This invention relates to a new and improved roofing especially adapted for use in 10 recovering old roofs.

My invention contemplates the use of composition roofing in strip form, the strips being especially manufactured and designed 15 for application from eave to ridge instead of from side to side as is customary with strip or roll roofing.

There has long existed an urgent demand 20 for some practical means for applying strip or roll roofing to old roofs and particularly old shingle roofs. The difficulties that confront one in applying composition roofing to roofs and especially in seeking to recover with composition sheets an old shingle roof 25 are of a serious nature, especially where the old shingles are applied over widely spaced strips of decking or sheeting. They generally present an irregular surface and are too rotten to permit the nails utilized for fastening 30 the composition roofing to take any lasting anchorage therein. The result has been that the expansion and contraction of the composition roofing has rapidly drawn loose the fastening nails which were embedded 35 only in the shingles, thus permitting the roofing strips to become loose and to be blown away. In fact it is now the general 40 opinion of those skilled in the art that strip roofing cannot be successfully applied over an old shingle roof with side by side spaced roof sheathing.

The method and the preferred means for carrying the method into effect which form the subject matter of this invention are the 45 result of many years careful and exhaustive experiment in the recovering of old shingle roofs which present problems peculiar to themselves and differing fundamentally from the solidly sheathed roof. The essential feature 50 of this invention consists in the utilization of very thin, light, flexible strips of wood or like material which will not have sufficient body in themselves to warp or pull loose from the roof to which it is applied 55 as a lattice frame; which will be sufficiently flexible to conform readily to curves and

angles of a roof, where not too sharp; and which will possess just sufficient body to be firmly anchored by their retaining nails to the decking or sheathing and rafters and to 60 afford a sufficient anchorage for the fastening nails for the roofing strips so as to insure their holding. It is important that the strips be only thick enough to afford the necessary nail anchorage as otherwise they 65 will pull away from the roof sheathing or from the composition strips and prove wholly impractical.

My invention further contemplates the utilization of a strip wider than the overlap 70 given the side edges of adjacent composition roofing strips so that it will project beyond the joint and thus better support it and the thick layer of cement which is interposed between said lapped edges, the retaining nails 75 being driven down through the lapped roofing edges into the retaining strips while the cement is soft so that it serves to seal the nail hole.

These and other advantages will be better 80 understood by reference to the accompanying drawings which form a part of this specification, and in which a typical roof is shown in transverse section in Fig. 1 with one strip of roofing rolled up at its lower end to expose the old roofing and show an attaching strip and the cement layer applied ready for 85 the raised roofing to be laid. Fig. 2 is a typical plan of part of a roof showing the lattice arrangement of the attaching strips. 90

Similar reference numerals refer to similar parts throughout the drawings.

As illustrated, I show a typical roof supported by rafters 1 on which are spaced sheathing or decking strips 2 to which are 95 nailed the shingles 3. To cover such a roof with composition roofing, I first lay on top of the shingles a thin wooden attaching strip 4 which at suitable intervals is attached by means of nails 5 to the sheathing and where 100 possible to the rafters so as to insure a firm and permanent attachment. This strip is preferably from a quarter to three-eighths of an inch in thickness by two and one-half to three inches wide and possesses sufficient 105 flexibility to conform to any ordinary curves or gentle bends or breaks in the roof. For sharp breaks it is only necessary to partly cross-cut the strip so that it can be bent to shape itself to the roof. This strip is laid to 110 run from the eaves to the butt of the top horizontal row of shingles at the ridge and

after being fastened a second strip, similar thereto and parallel therewith, is applied to the roof and spaced on centers corresponding approximately to the width of the roofing strips 6 which are to be applied. These strips may be of any suitable design for being laid from eave to ridge and the first section of roofing laid is attached along one edge to one of the strips 4 by nails 7 which are driven through the strip 4 and the shingles and are long enough to enter the sheathing and the rafters where the latter are in line. Having secured one side edge of a roofing section in place the latter is permitted to assume a natural position on the roof with its other edge overlapping an adjacent strip 4 in the direction in which the work is to be carried.

One side edge of each roofing section should come even with the far edge of one strip and its other side edge should stop from one-half to an inch short of the far edge of the other strip 4. A thick heavy layer 8 of roofing cement of any suitable character is then applied over the underlying edge of the roofing section which rests on the strip and the edge of the next roofing section is applied so as to overlap the cemented edge of the first mentioned roofing section and partly overlap the strip 4. The overlapping edges of the roof sections 6 are then made fast by nails driven through them and the cement layers and through the underlying strip into the shingles, sheeting or rafters where the latter are in line, and one complete section of the roof has thus been laid.

Strips 9 are laid along the eave and strips 10 along on both sides of each hip so as to provide a firm means for attaching the top and bottom edges of the strips in position. The strips throughout run straight up from eave and abut against the bases of the shingles forming the top horizontal row at the ridge, the shingles or other means forming the ridge or hip combs having been first removed. The ends of the roofing strips 6 are nailed securely to the top sheathing board at ridge and to the eave strip 4. I thus avoid any loose or unsecurely attached edge for any of the roofing section. When the roof has been applied it will be observed that there is but a slight hardly noticeable ridge formed by the attachment strips 4 and I thus avoid spoiling the appearance of the roof and I allow just enough sag crosswise of the roofing sections 6 to take care of their natural expansion and contraction. It is also to be noted that the thin strips 4 will form a permanent attaching frame or lattice because by reason of its thinness its expansion and contraction will not tend to pull it loose from the sheathing boards. If a thick strip were used it would have more strength and would pull the nails out and work loose. Moreover, if a thick strip were used on roofs having curves it will bulge in places tearing the roof,

whereas thin flexible strips will conform to and will remain rigidly in position on the roof as originally applied and will effectively protect the roofing from being broken or torn.

A further advantage of the thin strip is that it will support only a negligible portion of the composition roofing clear of the shingles. There is therefore a minimum of danger of the composition roof being broken through by stones or other articles falling on the roof or even by one stepping thereon. Moreover, the thin wide strips serve to raise the joints of the composition roofing just enough to cause the water to shed therefrom, the exposed joint being spaced inwardly from the underlying strip edges so that it is fully supported thereby as well as protected from water.

Having thus described my invention, what I claim as new and desire to secure by Letters Patent, is:

1. A roof construction comprising the combination with spaced sheathing boards having wooden shingles nailed thereon, of thin wide flexible wooden strips laid over the old shingles and nailed to the sheathing boards, said strips extending in spaced relation substantially from eave to ridge of the roof, sheets of composition roofing laid with their adjacent side edges overlapping each other and said strips, a layer of cement interposed between the lapped sheet edges above said strips, and a row of roofing nails driven down through the lapped sheet edges and the interposed cement into each of said wooden strips to secure the composition roofing thereto.

2. A roofing comprising the combination with an old shingle roof having spaced sheathing boards, of thin wide flexible attaching strips laid over the old shingles along the eave and on each side along the hips, and vertical strips rising from the eave strips to the butts of the top horizontal row of shingles along the ridges, composition roofing laid in sheets extending from eave to ridge or hip, each sheet having one side edge overlapping an attaching strip and its other side edge overlapping the adjacent edge of a sheet which itself overlaps another of said attaching strips, a layer of cement interposed between each pair of overlapping edges of the roofing sheets, fastening nails driven through the lapped edges of the roofing sheets the interposed cement and the underlying attaching strips into the underlying sheathing boards and shingles, and means to fasten said attaching strips to the sheathing boards, substantially as described.

3. The herein-described means for the laying of composition roofing over old shingle roofs having spaced sheathing boards, which comprises in combination with an old shingle roof having spaced sheathing boards there-

under, a lattice work formed of thin wide flexible strips laid over the old shingles and extending along the eaves and along the hips and from eaves to ridge and hips, the strips 5 running from eave to ridge or hip being spaced substantially the width of the composition sheets to be applied, means to attach said lattice strips to the sheathing boards, and means to secure the marginal edges of 10 the composition roofing sheets to the strips forming said lattice work.

4. The herein-described method for laying a composition roof over old shingle roofs having spaced sheathing boards, which consists in laying thin flexible attaching strips 15 over the old shingles at right angles to the eave, said attaching strips extending approxi-

mately from hip to ridge, spacing said latter strips to correspond substantially to the width of the composition roofing sheets to be 20 applied, applying the composition roofing sheets over the old shingles from eave to ridge or hip with their side edges overlapping each other and said attaching strips, nailing the attaching strips to the sheathing 25 boards, applying cement between the lapped roofing edges, and nailing the lapped edges through the attaching strips into the underlying sheathing boards and shingles before the cement has set, substantially as described. 30

In testimony whereof I affix my signature.
CHARLES B. JAYNES.
